BREAD SLICING MACHINE

Arthur A. Kottmann, Davenport, and Fred L. Bennett, Le Claire, Iowa, and Edward R. Keast, West Englewood, N. J., assignors, by mesne assignments, to The Bettendorf Company, a corporation of Maryland

Application November 30, 1940, Serial No. 367,998

6 Claims. (Cl. 146—88)

This invention relates to bread slicing machines of the endless band slicer type, and more particularly to means for preventing accumulation of solid material on the blade surfaces.

It has been found that when slicing certain varieties of bread, such as rye bread and some types of white bread, a glutinous deposit is built up on the blades and on the pulleys which drive the blades. This deposit cakes on the blades and pulleys and causes heating of the blades because of friction developed at the point where the blades pass through the guiding fingers. This increase in blade temperature is sufficient to bake the gluten deposit so that it is extremely hard and difficult to remove. The gluten deposit causes excessive wear on the guide fingers and also, due to the heat developed by friction, the blades are lengthened and the tension of the blades reduced with the result that the slices become uneven.

One object of the present invention is to provide for continuously lubricating the side surfaces of the blades to lessen the tendency of the glutinous material to adhere to the blades.

Another object of the invention is to provide means for continuously removing any material adhering to the blade surfaces or to the surfaces of the pulleys.

With the above and other objects in view, the invention may be said to comprise the lubricating and cleaning means illustrated in the accompanying drawings hereinafter described and particularly set forth in the appended claims, together with such variations and modifications thereof as will be apparent to one skilled in the art to which the invention pertains.

Reference should be had to the accompanying drawings forming a part of this specification, in which:

Figure 1 is a diagrammatic side elevation of a band blade slicer showing the invention applied thereto;

Fig. 2 is a fragmentary side elevation on an enlarged scale showing the lubricating and scraping devices associated with one of the blade pulleys;

Fig. 3 is a fragmentary side elevation on an enlarged scale showing the lubricating and scraping device associated with the other pulley;

Fig. 4 is a fragmentary front elevation of one end of the blade lubricating and scraping device, portions being broken away and shown in section;

Fig. 5 is a fragmentary front elevation of the opposite end of the blade lubricating and scrap-

ing device with a portion of the lubricating device broken away and shown in section;

Fig. 6 is a section taken on the line indicated at 6—6 in Fig. 4;

Fig. 7 is a section taken on the line indicated at 7—7 in Fig. 2; and

Fig. 8 is a section on the line indicated at 8—8 in Fig. 7.

In the accompanying drawings, the devices of the present invention are shown applied to the slicing unit of a bread slicing machine, which comprises spaced pulleys 1 and 2 journaled in frame members 3 and crossed endless slicer blades 4 running over the pulleys. The bread is fed to the slicer blades along a bed 5 which is slotted to permit passage of the slicer blades. Suitable guide fingers 6 may be provided to hold the portions of the blades passing through the bed 5 in parallel planes. A series of the blades 4 are arranged side by side, as shown in Figs. 4 and 5, the spaces between the blades where they pass through the bed 5 corresponding to the thickness of the slices to be cut.

Adjacent the uppermost drum 4 there is mounted a lubricant applying wiper block 7 which is pressed against the outer surfaces of the blades as they pass over the drum 4, the inner face of the block 7 being shaped to conform to the surface of the drum and the block being of a length sufficient to engage all of the blades passing over the drum. A longitudinal slot 8 extends the full length of the block 7 and opens to the inner face of the block. The slot 8 has an absorbent pad 9 therein, which is impregnated with a lubricant and serves to maintain a supply of lubricant to the inner face of the block, so that the bands are continuously moistened with lubricant. Lubricant may be supplied to the pad 9 through oil passages 10 leading to an oil receiving channel 11 in the top of the block 7.

Lubricant is applied to the surface of the upper pulley 1 by means of an elongated wiper block 12 which engages the underside of the pulley 1 between the runs of the endless slicer blades 4. The block 12 has an inner face which conforms to the surface of the pulley and is provided with a slot 13 opening to the inner face thereof, in which is mounted an absorbent pad 14 which is supplied with oil through passages 15 leading from an oil receiving channel 16 formed in the block. The block 12 preferably projects beyond an end of the pulley 1, as shown in Fig. 7, a sufficient distance to expose an end portion of the channel 16, so that oil may be introduced into the channel 16.

Lubricant is supplied to the surface of the lower pulley 2 by means of an elongated wiper block 17 which is provided with a slot 18 opening to its inner face, in which is mounted an absorbent pad 19 which is supplied with oil through passages 20 leading to an oil receiving channel 21, as shown in Fig. 3.

The blocks 12 and 17 continuously supply oil to the surfaces of the pulleys 1 and 2, and the oil on these pulleys moistens the inner surfaces of the slicer blades. The outer surfaces of the blades are continuously moistened by the lubricant applying wiper block 7, and the lubricant on the side faces of the blades greatly lessens the tendency of glutinous material in the bread to stick to the surfaces of the blades.

Each of the lubricant applying blocks is yieldingly pressed toward the surface of a drum and each of the blocks is mounted upon a support which is detachably secured to the frame members 3 which support the pulleys. Each wiper unit is mounted upon a supporting bar 22 detachably secured to the frame members and disposed parallel with the pulley axes. Each supporting bar 22 is a square bar having one end fitting in a square hole in a supporting plate 23 attached to one of the frame members 3. The opposite end of each of the bars 22 is provided with a bore 24 which receives a plunger 25 which is pressed outwardly by a coiled spring 26 interposed between the inner end of the plunger and the bottom of the bore 24. A retaining pin 27 engaging a slot in the plunger 25 prevents separation of the plunger from the bar 22. At its outer end the plunger is provided with a shoulder 28 and a reduced end 29 which fits in a hole provided in a supporting plate 30 attached to the frame member 3 opposite that to which the plate 23 is attached.

The wiper block 7 is carried by an angle bar 31 which has a vertical flange 32 rigidly attached to the supporting bar 22 and is resiliently supported by means of a spring plate 33 which is secured by bolts 34 to the vertical flange 32. The spring plate 33 projects above the bar 31 and is adjustably connected to the bar 31, the plate being provided with slots 35 which receive the attaching bolts 34. By loosening the bolts 34 the plate 33 and the block 7 may be adjusted vertically to increase or decrease the spring pressure exerted on the block 7 by the plate 33. The block 7 is attached to the plate 33 by means of screws 36. The bar 31 has an inwardly projecting flange 37 to which is attached a resilient scraper blade 38 which engages the outer faces of the slicer bands. The scraper blade 38 is adjustably connected to the flange 37, being provided with elongated slots 39 which receive attaching bolts 40. By adjusting the scraper 38 inwardly toward the pulley 1, the pressure of the scraper on the blades may be increased.

The wiper block 12 is supported upon an angle bar 41 which is rigidly attached to the removable cross bar 22 which is mounted directly beneath the top pulley 1. The block 12 is carried by spring plate 42 attached to the bar 41 and this plate is preferably adjustably secured to the bar 41 so that the spring pressure exerted by the block on the drum may be increased or decreased. To permit this adjustment, the spring plate 42 may be provided with slots 43 to receive attaching bolts 44, which serve to secure the plate in adjusted positions on the bar 41. The supporting bar 41 may be adjustably connected to the bar 22 by bolts 44a passing through slots 43a in the

bar 41. A scraper 45 is attached to the bar 22 on the side opposite that to which the bar 41 is attached and has its upper edge in engagement with the surface of the pulley 1. The scraper 5 is preferably adjustably secured to the bar, being provided with slots 46 which receive attaching bolts 47, by means of which the scraper may be secured in adjusted position. A guard plate 48 may be secured to the bar 22 by the bolts 47 and this guard plate coacts with the scraper to provide a receptacle to receive any solid material dislodged from the surface of the pulley by the scraper.

As shown in Fig. 3, the wiper block 17 which engages the lower pulley 2 is supported on an angle bar 49 rigidly attached to the lower supporting bar 22, the block 17 being carried by a spring plate 50 which is adjustably attached to the angle bar 49. The adjustment of the block 17 is permitted by slots 51 in the plate 50 which receives attaching bolts 52. Downward adjustment of the block 17 causes increased deflection of the spring plate 50 and results in greater spring pressure on the surface of the drum. A scraper 54 is clamped between the bar 49 and the lowermost bar 22 and is preferably adjustable to vary its pressure against the drum surface. The inner edge portion of the scraper 54 and the bar 49 may be provided with transverse slots 55 and 55a which receive clamping bolts 56, which serve to secure the bar 49 and scraper 54 in adjusted position. A guard plate 57 may also be secured to the lowermost supporting bar 22 to prevent the particles of solid material dislodged by the scraper 54 from flying into adjacent parts of the machine.

In the operation of the machine, the interior and exterior surfaces of the blades and the surfaces of the pulleys are continuously supplied with a liquid lubricant. The lubricant on the side faces of the blades lessens the adhesion between the blades and glutinous material of the bread being sliced. Any glutinous material adhering to the exterior surfaces of the bands is removed by the scraper 38, and any glutinous material adhering to the surfaces of the pulleys 1 and 2 is removed by the scraper blades 45 and 54. It has been found that most of the adhesive material on the interior surfaces of the slicer blades is transferred to the surfaces of the pulleys during passage of the blades over the pulleys, and that the cleaning of the pulley surfaces serves to prevent any substantial accumulation of solid material on the inner surfaces of the slicer blades. The lubricant used is preferably an oil such as that known in the trade as "divider oil" which is a light, colorless, odorless and tasteless oil of vegetable origin. The wooden wiper blocks are preferably made of hard maple since this material has been found to have superior wearing qualities.

It is essential that both the lubricant applying block 8 and the scraper 38 engage the blades 4 at points where the blades are in full engagement with a rigid surface, such as the cylindrical surface of the pulley 1, so that the depth of grooves worn in the block and scraper by the blades cannot exceed the thickness of the blades. If the block or scraper were engaged with an unbacked portion of the blades, deep grooves would be worn in the block or scraper by the cutter blades which would interfere with adjustment of the blades on the pulleys to vary the thickness of the slices cut by the blades. By positioning the block 7 and the scraper 38 to engage the blades in the arc of contact of the blades with the pulley 1,

where they are in full engagement with the pulley 1, the grooving of the scraper and block is so slight that the blades are not damaged when set to a different spacing.

It is to be understood that variations and modifications of the specific devices herein shown and described for purposes of illustration may be made without departing from the spirit of the invention.

What we claim is:

1. In a bread slicing machine having a pair of spaced pulleys and a series of endless cutter blades passing over said pulleys, means for moistening the peripheral blade engaging surfaces of said pulleys with a lubricant, a lubricant applying wiper bearing against the external surfaces of the cutter blades on one of said pulleys, a scraper engaging the periphery of each pulley throughout the length of the blade engaging portion thereof, and a scraper engaging the outer surfaces of the cutter blades on one of said pulleys.

2. In a bread slicing machine having a pair of spaced pulleys and a series of spaced endless cutter blades running over said pulleys, a lubricant applying wiper comprising a wood block having an inner face shaped to conform to the surface of a pulley, a slot opening to said inner face, a lubricant impregnated pad in said slot, and means for yieldingly pressing said block toward the surface of the pulley.

3. In a bread slicing machine having a pair of spaced pulleys and a series of spaced endless cutter blades running over said pulleys, a combined lubricating and scraping device comprising a supporting bar parallel with and adjacent a pulley, a lubricant applying wiper resiliently supported by said bar, and a resilient scraper carried by said bar, said wiper and scraper engaging the outer surfaces of cutter blades on the adjacent pulley.

4. In a bread slicing machine having a pair of spaced pulleys and spaced endless cutter blades

running over said pulleys, a lubricating applying and scraping device comprising a fixed bar parallel with and adjacent to a pulley, a resilient supporting member attached to said bar, a lubricant applying wiper carried by said resilient member and yieldingly pressed against the pulley, said resilient member being adjustable to vary the pressure of the wiper against the pulley, and a resilient scraper attached to said bar 10 and yieldingly pressed against the pulley, said scraper being adjustable on the bar to vary the pressure thereof against the drum.

5. In a bread slicing machine having a pair of pulleys and a series of flat endless cutter blades 15 spaced apart and running over said pulleys, a wiper block extending longitudinally of one of said pulleys and engaging the same between the opposite runs of said blades, a wiper block extending longitudinally of one of said pulleys and 20 engaging the exterior surfaces of the blades running over the latter pulley, said blocks having concave faces conforming to the pulley curvature, a lubricant retaining pad carried by each of said wiper blocks for applying lubricant to the surfaces of the blades and pulleys, and means for yieldably pressing each wiper block against the pulley adjacent which it is mounted.

6. In a bread slicing machine having a pair of spaced pulleys and a series of flat spaced endless cutter blades running over said pulleys, a lubricant applying wiper engaging the exterior surfaces of said blades in the arc of contact of the blades with one of said pulleys, said wiper comprising a block having a concave blade engaging face conforming to the curvature of the pulley, a longitudinal slot opening to its blade engaging face and a lubricant impregnated pad in said slot, and means for yieldably pressing said wiper against said blades.
